UNITED STATES PATENT OFFICE.

CHARLES C. WIENTGE, OF PROVIDENCE, RHODE ISLAND, ASSIGNOR TO THE HOWARD STERLING COMPANY, OF SAME PLACE.

DESIGN FOR A SPOON, &c.

SPECIFICATION forming part of Design No. 21,441, dated March 29, 1892.

Application filed February 24, 1892. Serial No. 422,691. Term of patent 7 years.

To all whom it may concern:

Be it known that I, CHARLES C. WIENTGE, of Providence, in the county of Providence and State of Rhode Island, have invented and 5 produced a new and original Design for Handles of Spoons, Forks, &c., of which the following is a specification, reference being had to the accompanying drawings, forming part thereof.

10 Figure 1 is a front elevation of a spoon provided with a handle, showing my new design. Fig. 2 is a rear elevation of the handle.

The leading feature of my design consists in the peculiar and novel arrangement of foliated scrolls forming the border of the outline 15 of the handle and foliated pendants in the center of the ornamentation in the Louis Quatorze style of ornamentation, as will be more fully set forth hereinafter.

20 In the drawings the two beads 3 extend from the bowl upward along the margin of the handle and terminate in the foliated upper ends 4. From these foliated ends extend the scrolls 5, forming the margin of the handle and inclosing the approximately oval shell 25 or field 6. The scrolls 5 have their upper ends

foliated, the inner portion turning toward the center and the outer portion forming the foliated outwardly-curved extension 7, within which are supported the scrolls 8, inclosing 30 the heart-shaped shell or blank 9, the whole being surrounded by the curled leaves 10. On the front of the handle the scrolls 8 are each ornamented by a row of pin-heads, and from the scrolls the foliated pendant extends partly 35 over the shell 6. On the front of the handle the foliated pendant 12 extends from the lower part of the scrolls 5, and near the lower end of the handle the beads 13 are placed between the beads 3. The lower ends, being 40 twisted, extend to the bowl. On the rear of the handle the pendant 12 and the beads 13 are omitted.

What I claim is—

The design for handles of spoons and forks, 45 herein shown and described.

In witness whereof I have hereunto set my hand.

CHARLES C. WIENTGE.
